COMBINED ELASTIC BELT AND
SUSPENDERS

Lewis F. Palkens, Nashua, N. H.

Application July 9, 1932, Serial No. 621,704

2 Claims. (Cl. 2—41)

This invention relates to improvements in belts and pertains particularly to a combined reducing belt and clothing suspending means.

The primary object of the present invention is 5 to provide an elastic belt designed primarily for use by stout persons desiring to reduce the waist girth and having a suspending means associated therewith which serves to retain the belt in proper position.

10 Another object of the invention is to provide an elastic reducing belt having a suspension means connected therewith which also serves as a means for supporting a garment such for example as trousers.

15 A still further object of the invention is to provide a combined elastic reducing belt and garment supporting means, which will be comfortable to the wearer and which will not interfere in any way with the wearing of other articles of clothing.

20 The invention will be best understood from a consideration of the following detailed description taken in connection with the accompanying drawing forming part of this specification, with the understanding, however, that the invention is not confined to any strict conformity with the 25 showing of the drawing but may be changed or modified so long as such changes or modifications mark no material departure from the salient features of the invention as expressed in the appended claims.

30 In the drawing:—

Figure 1 is a view in perspective of the belt embodying the present invention showing the same in use;

35 Figure 2 is a perspective view of the belt per se, viewing the same from the front and showing the manner in which the shoulder supporting straps are joined thereto at the back.

40 Referring now more particularly to the drawing wherein like numerals of reference indicate corresponding parts throughout the several views, it will be seen that the belt embodying the present invention and which is indicated as a whole by the numeral 1, is of substantial width. This belt is designed to encircle the body at the waist and is 45 made of elastic web material of the character commonly employed for elastic garments of this character. The belt is preferably formed of a single strip of the elastic material and it is formed by bringing the two end portions 2 thereof into 50 edge opposed relation and connecting them by the inner and outer vertical tapes 3 and 4.

55 By using the two tapes for connecting the edges 2 of the belt this portion of the belt is materially reinforced or stiffened as the tapes 3 and 4 are of

relatively heavy and non-elastic fabric and, therefore, the necessary transverse stiffening is imparted to the belt to prevent its wrinkling or buckling and the use of the usual stiffening elements such as bone or steel is avoided.

5 Connected to the outer side of the belt at the rear, which is at a point diametrically opposite the tapes 3 and 4, are the ends of a pair of straps each of which straps is indicated by the numeral 5. These ends of the straps 5 are indicated by the 10 numerals 6 and as shown they are stitched at 7 to the outer face of the belt and in side by side relation. The straps are arranged in crossed relation as shown and each has its other end stitched as at 8, to the front of the belt at one 15 side of the center thereof which is defined by the connected edges 2. While the distance between the connected edges of the belt and the points where the front ends of the straps 5 are connected thereto may be varied as desired, it is 20 preferable that each of the front ends be spaced approximately five inches from the connected edges of the belt. It has been found that by connecting the straps at these points with respect to the central front part of the belt, they are properly located to pass between the front and back 25 tails of the shirt of a wearer so that the front ends of the straps may be attached to the trousers of the wearer in the manner hereinafter described.

30 As shown in Figure 1, where the belt is shown applied to the body 9, the trousers 10 of the wearer have secured to the inner surface thereof at opposite sides of the front opening, the buttons 11.

35 These buttons are spaced from the front opening of the trousers a distance equal to the spacing of the front ends of the straps 5 from the connected ends 2 of the belt.

40 The front ends of the straps 5 have secured thereto the closed eye hooks 12 which depend therefrom and which are adapted to engage the buttons 11 when the belt is in use.

45 It will be noted that the hooks 12 are located above the lower edge of the belt so that when the belt is in use and the hooks engaged with the buttons 11 the buttons will be prevented from pressing directly against the side of the wearer of the belt by the body of the belt itself. It will also be apparent that by providing the straps for the belt not only is means afforded for supporting the trousers or other garment but the belt will be 50 prevented from slipping down into an uncomfortable position.

55 From the foregoing it will be readily apparent

that a device of the character herein disclosed constitutes an efficient means for reducing the waist line and also provides means for supporting a garment therefrom.

5 Having thus described the invention, what is claimed is:—

1. A device of the character described, comprising a relatively broad elastic band designed to encircle the waist and constituting a reducing belt, a pair of shoulder straps each connected at one end in relatively close relation at the back of the belt and extending in crossed relation to the front of the belt and having their front ends relatively widely spaced apart and connected to the outer face of the belt at a point substantially midway between the top and bottom edges thereof, means at the front ends of the shoulder straps for connecting the same with the belt, said belt being formed of a band of material having the ends brought into end opposed relation substantially midway between the front ends of said straps and yieldable reinforcing elements extending transversely of the inner and outer faces of the belt for the full width of the latter and having said opposed ends therebetween and secured thereto, said reinforcing elements being relatively narrow and positioning over the abdomen when the belt is in use.
- 10 2. A device of the character described, comprising a relatively broad elastic band designed
- 15
- 20

to encircle the waist and constituting a reducing belt, a pair of shoulder straps each connected at one end in relatively close relation at the back of the belt and extending in crossed relation to the front of the belt and having their front ends relatively widely spaced apart and connected to the outer face of the belt at a point substantially midway between the top and bottom edges thereof, means at the front ends of the shoulder straps for connecting the same with the belt, said belt being formed of a band of material having the ends brought into end opposed relation substantially midway between the front ends of said straps and yieldable reinforcing elements extending transversely of the inner and outer faces of the belt for the full width of the latter and having said opposed ends therebetween and secured thereto, said reinforcing elements being relatively narrow and positioning over the abdomen when the belt is in use.
